MULTI-BEAM LAMP

De Warren Bridges, 5435 Skyway St., Paradise, Calif.

Filed Feb. 23, 1962, Ser. No. 68,953

Term of patent 14 years

(Cl. D48—20)

Fig. 1.

Fig. 2.

Fig. 3.

Fig. 4.

The dominant features of my design reside in the portions shown in full lines.

I claim:

The ornamental design for multi-beam lamp, as shown and described.
